DESIGN FOR AN AUTOMOBILE LIGHT SIGNAL

Byron E. White, Brattleboro, Vt.

Application April 16, 1937, Serial No. 68,822

Term of patent 14 years

To all whom it may concern:

Be it known that I, Byron E. White, a citizen of the United States, residing at Brattleboro, in the county of Windham and State of Vermont, have invented a new, original, and ornamental Design for an Automobile Light Signal, of which the following is a specification, reference being had to the accompanying drawing, forming part thereof, in which:

Figure 1, is a front elevation of the automobile light signal, showing my new design,

Figure 2 is a top plan view of the same;
Figure 3 is a rear elevation of the automobile light signal;

Figure 4 is an end elevation thereof.

I claim:

The ornamental design for an automobile light signal, as shown.

BYRON E. WHITE.
